UNITED STATES PATENT OFFICE.

JACOB R. SNYDER, OF CLEVELAND, OHIO, ASSIGNOR TO THE STAR REBOUND CONTROLLER COMPANY, OF CLEVELAND, OHIO, A CORPORATION OF OHIO.

REBOUND CONTROLLER.

Application filed April 20, 1923. Serial No. 633,508.

To all whom it may concern:

Be it known that I, JACOB R. SNYDER, a citizen of the United States, residing at Cleveland, in the county of Cuyahoga and 5 State of Ohio, have invented a certain new and useful Improvement in Rebound Controllers, of which the following is a full, clear, and exact description.

This invention relates to rebound controllers or so-called snubbers adapted to be connected between relatively movable bodies, and particularly between the body and axle or running gear of a motor vehicle to 10 check rebound movements of the body following the sudden compression of the main springs.

More particularly the present invention is an improvement over the construction constituting the subject matter of my prior application Serial No. 548,923, filed April 3, 15 1922, the chief object being to improve the operation and the construction as well as to simplify and reduce the cost of the construction.

20 The invention may be briefly summarized as consisting in certain novel details of construction, and combinations and arrangements of parts which will be described in the specification and pointed out in the appended claims.

In the accompanying sheets of drawings wherein I have shown the preferred embodiment of my invention, Fig. 1 is a vertical sectional view through the rebound controller; Fig. 2 is a face view with parts removed looking at one part of the casing and certain parts normally enclosed therein; Fig. 3 is a similar view with certain additional parts including the coil spring removed; Fig. 4 is a view substantially the same as Fig. 3 but showing a slight modification; Fig. 5 is a side view of the combined spring support and friction member which is adapted to engage the rotatable drum; Fig. 6 is a fragmentary perspective view of the same; and Fig. 7 is a sectional view substantially along the line 7—7 of Fig. 5 looking in the direction indicated by the arrows and showing additionally, a part of the casing.

The present rebound controller or snubber is of the general type of that illustrated in my prior application referred to, in the respect that it includes a frictionally resisted rotatable drum adapted to rotate about a

center bolt by which the device may be secured in place on the chassis frame or other member, a flexible member or belt which is coiled on the drum and adapted to be connected to the axle (assuming that the device is used on a vehicle, for which it is particularly adapted), a coil spring, which also surrounds the center bolt, a casing which encloses the parts referred to, and certain auxiliary parts such as an exteriorly adjustable spring by which the pressure of the friction members on opposite sides of the drum may be adjusted. The drum is rotated both when the belt is unwound from it, i. e. during the rebound stroke, and when the belt is again wound onto the drum during the compression stroke of the main spring, and to bring this about the outer end of this spring may be, and preferably is connected to the inner end of the belt.

I will now describe the detailed construction of the rebound controller, pointing out the novel features or present improvements which are set forth in the appended claims.

The center bolt referred to, is shown at 10, this bolt extending centrally through the casing and projecting from both sides thereof, the projecting part on one side being adapted to receive any suitable fitting by which the device may be attached to the 15 member which is adapted to carry it, which member is generally the chassis frame of a vehicle.

Clamped against a shoulder 10^a of the center bolt by a nut 11 is a cup-shaped part 90 or half 12 of the casing. The other part of the casing which is also cup-shaped and telescopes with the part 12 is shown at 13. The middle part of the casing member 12 is concaved or tapered inwardly forming a space 95 to receive the nut 11, the conical face being indicated at 12^a.

Inside the casing and rotatable about an enlarged part 10^b of the center bolt, is the drum 14, which drum is preferably formed 100 of oil impregnated wood so as to be self-lubricating as in my prior application. The drum on one side has a concave face which bears against the inwardly concave face 12^a of the cup 12, the latter constituting one of 105 the friction members for the drum.

Bearing against the opposite side of the drum 14 is a second friction member 15. While the drum engaging portion of this member 15 is in the form of a disk, other 110

portions formed integral with it perform additional functions to be referred to. It will be observed that the member 15 has an integral annular hub portion 15^a which surrounds the center bolt, and that the end of the hub portion is bent inwardly as shown at 15^b in substantial conformity with the portion 10^c of the center bolt which is flattened so that the member 15 will be held from turning, it being understood that both friction members which engage opposite sides of the drum are stationary. The in-turned part 15^b of the member 15 forms a relatively short bearing on the center bolt which allows a slight rocking movement to permit the drum engaging portion of the member 15 to at all times accommodate itself to the face of the drum.

It will be observed also that the central opening 14^a of the drum is tapered, and that the drum engages the center bolt only at or adjacent one side thereof. This improvement allows the drum to accommodate itself to the tapered face 12^a of the cup 12, so that whatever irregularities there may be in the assembly are compensated for, both the drum 14 and friction member 15 being susceptible of whatever slight rocking motions are necessary to maintain the firm engagement between the rotatable drum and the two non-rotating friction members on opposite sides of it.

The member 15 has between the annular hub portion designated 15^a and the inturned bearing portion 15^b, an annular shoulder 15^c forming a bearing and support for the central or middle part of the cup 13 of the casing, as clearly shown in Fig. 1 and Fig. 7.

At the side of the drum, and between the friction member 15 and the cup 13 is a coil spring 16, which is preferably formed of flat steel as in my prior application. In connection with this spring the hub portion of the member 15 performs two additional functions. One of these functions is that of a spring collar, which in my prior construction was taken care of by a separate piece, and to that end the hub portion 15^a of the member 15 has an elongated opening 15^d depressed in it to receive the inner end 16^a of the spring. Still further, the hub portion 15^a of this member has an outwardly depressed spring supporting portion 15^e which is located adjacent the depression 15^d and supports the innermost convolution of the spring adjacent the inturned end 16^a, and thus prevents the spring being broken at this point as it shortly would be in actual practice if it were left unsupported.

It will be seen, therefore, that the member 15 serves as a friction disk for the drum, as a spring collar for the spring, as a support for the cup 13, and as a support for the innermost convolution of the spring.

As in my prior application, the frictional

resistance between the drum and the stationary friction members on opposite sides of it is produced by a cup-shaped spring arranged exteriorly of the casing and capable of being adjusted to increase or decrease the resistance to rotation. This spring, which is shown at 17, bears against the casing member 13 so as to press it and the friction member 15 inwardly against the drum, and the latter against the face 12^a of the casing member 12. This spring 17 is supported by an adjustable screw 18 engaging in a threaded opening in the end of the center bolt and adjustable to vary the pressure produced by the spring 17. A pointer or indicator 19 is pressed against the center part of the spring 17 by the head of the screw 18 and turns with the screw to serve as an indication of its tension or compression.

Coiled on the drum is a flexible connecting member preferably in the form of a belt 20 which extends out through an opening in the peripheral portions of the members 12 and 13 of the casing, and is designed to be attached to the axle or running gear of the vehicle when the center bolt 10 is attached to the chassis. The inner end of the belt is preferably faced with metal, and if desired, the metal facings may consist of one strip 21 doubled upon itself, and if desired, that portion of the strip on the outer face of the belt may have guide flanges 21^a for the outermost convolution or wrapping of the belt.

In my present construction as in my prior application, the coil spring, belt and drum are so arranged and associated that the drum is rotated in both directions, the drum being rotated in one direction as the belt is pulled out when the body and running gear move away from each other, or during the rebound stroke of the main springs, and being rotated in the reverse direction so as to wind in the belt by the spiral spring when the body and running gear approach each other, or during the compression stroke of the main springs. In my prior application the inner end of the belt is connected to the outer end of the spring, and the spring keeps the belt tight enough on the drum to prevent any slippage of the belt on the drum as the belt is wound onto the drum, as well as when it is unwound, this result being accomplished by properly proportioning the strength of the coil spring and the friction of the friction members on the drum.

In the present instance a positive connection is provided between the belt and drum so as to render slippage between the two impossible, and this feature constitutes one of the improvements of the present invention. However, as in the prior case, the outer end of the spiral spring is preferably connected to the inner end of the belt. This connection is preferably made as in my prior ap-

pllication by means of a swivel hook 22 having a laterally extending shank 22^a extending across the periphery of the drum, and preferably held in a loop of the metal strip

5 21, which loop is preferably crimped into a groove of the shank as shown at 22^b to prevent endwise movement of the shank. The hook proper, to which the end of the spring is connected, is located at the side of the

10 drum so that it may swing inwardly and outwardly to accommodate itself to the varying size of the spring as the latter expands and contracts or is wound up.

The positive connection between the belt 15 and drum may be obtained in several ways, two of which I have illustrated in the drawings. For example, in Fig. 3 the belt is provided with the equivalent of dowel pins 23, which are carried by the metal enclosed inner part of the belt and project into radially disposed openings in the periphery of the drum. In Fig. 4 the positive connection between the belt and drum is taken care 20 or by providing a transverse groove 24 in the periphery of the drum and causing the shank 22 of the hook and the loop in the metal strip 18 to lie in this groove.

Thus it will be seen that I have simplified the construction and reduced the number of 30 parts by forming in one piece the friction member, the spring collar, spring support and casing cup support; also that the bearing of the friction member 15 on the center bolt and the central opening in the drum are 35 such that both the friction member 15 and the drum may accommodate themselves to irregularities which may exist if the axis of the center bolt 10 and the axis of the conical face 12^a do not exactly coincide as is sometimes the case. Finally, it will be seen that 40 though the outer end of the spring is attached to the inner end of the belt, these parts have a positive connection with the drum so as to prevent slippage of the belt 45 thereon.

While I have shown the preferred embodiment or embodiments of my invention, I do not desire to be confined to the precise 50 details shown, but aim in my claims to cover all modifications which do not involve a departure from the spirit and scope of my invention.

Having described my invention, I claim:

1. In a rebound controller, a rotatable 55 frictionally resisted drum, a belt coiled on the drum, a spring for keeping the belt taut and located at one side of the drum, the outer end of the spring being connected to the belt, and one of said parts having a positive connection with the drum.

2. In a device of the character described, a rotatable frictionally resisted drum, a belt wound on the drum and adapted to rotate the drum in one direction, and a spring for 60 rotating the drum in the reverse direction

and located at one side of the drum, the spring and belt being connected together and the belt being connected to the drum.

3. In a device of the character described, a rotatably support drum a stationary center 70 bolt therefor, a flexible connecting member wound on the drum and adapted to rotate it in one direction, a spring for keeping the belt taut, and a friction member engaging the drum, said friction member having 75 a portion surrounding the bolt and constituting a support for the spring.

4. In a device of the character described, a rotatable drum, a flexible connecting member coiled thereon, and adapted to rotate the 80 drum in one direction, a spring at the side of the drum for keeping the belt taut, and a friction member engaging the side of the drum and located between the drum and spring and having a portion extending outwardly beyond the spring.

5. In a device of the character described, a rotatable drum, a flexible belt coiled thereon and adapted to rotate the drum in one direction, a spring at the side of the drum 90 for keeping the belt taut, a friction member engaging the drum and having a portion extending outwardly beyond the spring, and means engaging said portion to cause pressure between said friction member and the 95 drum.

6. In a device of the character described, a drum a stationary center bolt therefor, a flexible connecting member coiled on the 100 drum and adapted to turn it in one direction as the connecting member is unwound, a spring for winding the connecting member on the drum, and a friction member engaging the side of the drum to oppose its rotation and having an integral hub which 105 the spring surrounds and which in turn surrounds the center bolt.

7. In a device of the character described, a drum a stationary center bolt therefor, a flexible connecting member coiled on the 110 drum and adapted to turn it in one direction as the connecting member is unwound, a spring for winding the connecting member on the drum, a friction member engaging the drum to oppose its rotation and having 115 a hub portion surrounding the center bolt, and a casing member having a seat on said hub portion.

8. In a device of the character described, a drum a stationary center bolt therefor, a flexible connecting member coiled on the 120 drum and adapted to turn it in one direction as the connecting member is unwound, a spring for winding the connecting member on the drum, and a friction member engag- 125 ing the drum to oppose its rotation and having a hub which the spring surrounds, and to which its inner end is connected said hub surrounding the center bolt.

9. In a device of the character described, 130

- a drum a stationary center bolt therefor, a flexible connecting member coiled on the drum and adapted to turn it in one direction as the connecting member is unwound, a 5 spring for winding the connecting member on the drum, and a friction member engaging the drum to oppose its rotation and having a hub which the spring surrounds and which in turn surrounds the center bolt, 10 said hub having an integral portion adapted to support the inner convolution of the spring adjacent the point where it overlaps the inner end of the spring.
10. In a shock absorber, a center bolt, a 15 drum rotatably supported on it, a thrust bearing member engaged by one side of the drum, a flexible connecting member coiled on the drum, a spring for keeping the same taut, the drum having a portion loosely 20 surrounding the center bolt so as to permit the drum to have a wobbling motion in maintaining contact with said thrust bearing.
11. In a device of the character described, 25 a center bolt, a drum rotatably supported thereon, a thrust bearing and friction member engaging one side of said drum, a flexible connecting member coiled on the drum, a spring associated with the connecting 30 member and drum, the drum having a nar-
- row bearing on the center bolt which enables a wobbling or rocking of the drum to compensate for irregularities while maintaining contact with said bearing and friction member. 35
12. In a device of the character described, a center bolt, a drum rotatably supported thereon, a flexible connecting member coiled on the drum, a spring for maintaining said flexible member taut, and a friction member 40 having a hub with a short bearing on the center bolt to enable said friction member to rock or wobble to compensate for irregularities. 45
13. In a device of the character described, a center bolt, a drum rotatably mounted thereon, a flexible connecting member coiled on the drum, means for maintaining the connecting member taut, a fixed thrust bearing engaging one side of the drum, a friction member engaging the opposite side of the drum, both said drum and said friction member having portions loosely surrounding the center bolt so as to permit of a rocking or wobbling motion to maintain the 50 drum in contact with said thrust bearing and compensate for irregularities. 55

In testimony whereof, I hereunto affix my signature.

JACOB R. SNYDER.
